(57) **CLAIM**

The ornamental design for a portable mount for a monitoring camera, as shown and described.

DESCRIPTION

FIG. 1 is a top, front, right-side perspective view of a portable mount for a monitoring camera showing our new design;

FIG. 2 is a bottom, front, right-side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the drawing views are included to illustrate environment only and form no part of the claimed design.

1 Claim, 7 Drawing Sheets
